UNITED STATES PATENT OFFICE

ROBERT U. LIPSCOMB AND EDWARD J. KUNSMAN, OF EL PASO, TEXAS

CHECK VALVE

Application filed August 7, 1931. Serial No. 555,775.

The present invention relates to check valves of the differential piston or balanced type.

The principal object of the invention is to provide a cushioning effect for the movements of the valves to minimize sudden action or hammering, in order to eliminate undue wear of the valve face and seat. Other objects are to provide a check valve which is easy to take apart for cleaning or repair, and which is inexpensive to construct and assemble.

The invention is herein shown and described as embodied in a boiler feed water check valve, but it may be used to equal advantage, without material change of form, in the discharge end of any devices for delivering fluids under pressure, such as piston type pumps, air compressors, injectors, inspirators, piston type feed water heaters, etc., and it may be used also in the suction portion of piston type pumps. It is to be understood, moreover, that changes, within the scope of the claims hereto appended, may be made in the form, construction and arrangement of the several parts, without departing from the spirit of the invention.

Reference should be had to the accompanying drawing in which

Fig. 1 is a vertical central section of a boiler check embodying the invention.

Fig. 2 is a horizontal section taken on the line 2-2 of Fig. 1.

In the drawing, the reference numeral 3 designates a body, which in the illustrated form of device is of T shape. At the lower end of the body is a connecting nipple 4 secured in place by a ground joint 5 and screw collar 6, and threaded at 7 to connect with the discharge of a feed water pump or injector, not shown. This is the inlet of the device.

The vertical portion of the body 3 communicates with the horizontal or side portion 3' through an orifice having a valve seat 8, with which the usual shut-off valve 9 is adapted to cooperate. The space 10 within the body portion 3' is the outlet of the device, and communicates directly with the boiler in the usual manner by means of a flanged joint 11.

12 is the stem for operating the shut-off valve 9 when desired. When the check valve is functioning, this valve 9 is open.

The upper end of the vertical body portion 3 carries an interior sleeve 13, connected therewith by a ground joint 14 and screw collar 15. The interior of this sleeve is formed with two cylinders of unequal diameters, the upper cylinder 16 being smaller than the lower cylinder 17. The upper end of the upper cylinder is closed, and is preferably provided with a screw plug 18. The wall of the sleeve 13, between the upper and lower cylinders, is provided with ports 19, which communicate with an annular space 20 between said sleeve and the body 3.

A pair of pistons 21 and 22 connected by a stem 23, operate in the cylinders 16 and 17 respectively. The lower and larger piston 22 has a valve face 24 adapted to cooperate with a seat 25 formed in the upper end of the nipple 4. This is the check valve proper. The lower end of the sleeve 13 is spaced from the seat 25, so that, when the pistons are elevated to open the valve, water can flow from the inlet 4 through the space 20, past the shut-off valve 9, and into the boiler through the space 10.

The space 26 within the sleeve 13 between the pistons 21 and 22 is open to boiler pressure through the space 20 and the ports 19. When the check valve opens by upward movement of the pistons, on account of increased pressure in the inlet 4, water is forced out through the ports 19, due to the differential effect of said pistons. The resistance of said ports to the outward flow raises the pressure within said space 26, thereby cushioning the opening movement of the valve, and preventing it from moving suddenly to the upper limit of its travel. When the pressure in the inlet 4 falls and the pistons begin to move downwardly to close the valve, the ports 19 restrict the flow of water into the expanding space 26, thereby reducing the pressure in said space and allowing the valve to close gently. Thus hammering is minimized in both opening and closing of the valve. The space 16 above the upper piston acts as an air

cushion to further prevent hammering on the upward movement of the pistons.

The usual relief needle valve 27 is provided to permit relief of pressure within the body 3 after the shut-off valve 9 has been closed and before the device is taken apart.

For any given area of the pistons 21 and 22, the principal cushioning effect is dependent upon the area of the ports 19. When the device is intended for use with gases instead of liquids, these ports may be made smaller than those shown. In the case of gases, the cushioning effect upon closing of the valve, although present to some extent, would be less than in the case of liquids.

15 We claim:

1. A check valve comprising a body having an inlet, an outlet, and a valve seat therebetween; a cylinder within said body, the end portions of said cylinder having different 20 diameters and its central portion having a restricted orifice connecting it with said outlet; connected pistons of different effective area operable within said cylinder portions, the outer face of one piston being exposed to the pressure of said inlet and the inner faces of both pistons being exposed to the outlet pressure within said cylinder; and a valve face carried by that piston which is exposed to the inlet pressure for cooperation with 25 said seat.

2. A check valve comprising a body having an inlet, an outlet, and a valve seat therebetween; a sleeve within and spaced from said body, said sleeve forming a cylinder, said cylinder having its end portions of different diameters and having a restricted orifice connecting its central portion with said outlet; connected pistons of different effective area 30 operable within said cylinder portions, the outer face of one piston being exposed to the pressure of said inlet and the inner faces of both pistons being exposed to the outlet pressure within said cylinder; and a valve face carried by that piston which is exposed to the inlet pressure for cooperation with 35 said seat.

3. A check valve comprising a body having an inlet, an outlet, and a valve seat therebetween; a sleeve within and spaced from said body, said sleeve being coaxial with said seat and having its end spaced therefrom, and said sleeve forming a continuous chamber with cylindrical end portions of different diameters and having its central portion in communication with said outlet; and connected pistons of different effective area exposed to the outlet pressure and operable in said cylinder portions, one of said pistons having a 40 valve face adapted for cooperation with said seat.

4. A check valve comprising a tubular body having an inlet at its lower end, a valve seat above said inlet, and an outlet in its side; a 45 sleeve within and spaced from said body, the

upper end of said sleeve closing the upper end of said body and its lower end being spaced above said seat, said sleeve forming a continuous chamber with cylindrical end portions of different diameters and having its central portion in communication with said outlet; and connected pistons of different effective area exposed to the outlet pressure and operable in said cylinder portions, one of said pistons having a valve face adapted for cooperation with said seat.

50 In testimony whereof we have signed our names to this specification.
